(57) **CLAIM**

The ornamental design for a bottle, as shown and described.

DESCRIPTION

FIG. 1 is a perspective view of a bottle in accordance with our design.

FIG. 2 is a front view thereof, it being understood that the rear view is a mirror image thereof.

FIG. 3 is a left side view thereof, it being understood that the right side view is a mirror image thereof.

FIG. 4 is a top view thereof; and,

FIG. 5 is a bottom view thereof.

The broken lines illustrate portions of the bottle that form no part of the claimed design.
